UNITED STATES PATENT OFFICE.

POMPEO PIERI, OF PARIS, FRANCE.

DESIGN FOR A REFLECTOR.

SPECIFICATION forming part of Design No. 29,791, dated December 13, 1898.

Application filed November 15, 1898. Serial No. 696,570. Term of patent 7 years.

To all whom it may concern:

Be it known that I, POMPEO PIERI, a subject of the King of Italy, permanently residing at Paris, France, and temporarily residing in the city, county, and State of New York, have invented and produced a new and original Design for Reflectors, of which the following is a specification, reference being had to the accompanying drawings, forming part

10 thereof.

Figure 1 is a plan view of my design, and Fig. 2 is a sectional view taken on the lines X X.

As shown in the drawings, the leading or 15 material feature of my design consists of a series of radiating grooves or corrugations A, cut in a convex reflector. The said grooves or corrugations radiate from a common cen-

ter B and are heavier nearest the common center and taper to a point at their outer extremity.

It is apparent that my design may be applied to reflectors for use with electric, gas, gasoline, or other kinds of light and for articles of similar nature.

Having described my invention, what I claim as new, and desire to secure by Letters Patent, is—

The design for a reflector, as herein shown and described.

In witness whereof I have hereunto set my hand in presence of two witnesses.

POMPEO PIERI.

Witnesses:

GEORGE G. SCHOENLANK,
OTTO MUNK.
